ATTORNEY

UNITED STATES PATENT OFFICE.

JOHN RIEKENS, OF WELLSBURG, IOWA.

WIRE-STRETCHER.

1,256,927.

Specification of Letters Patent. Patented Feb. 19, 1918.

Application filed October 5, 1916. Serial No. 123,960.

To all whom it may concern:

Be it known that I, JOHN RIEKENS, a citizen of the United States, residing at Wellsburg, in the county of Grundy and State of Iowa, have invented certain new and useful Improvements in Wire-Stretchers, of which the following is a specification.

The present invention has reference, generally, to improvements in wire stretchers. 10 The invention has more especial reference to a wire stretcher, which may be readily attached to a fence post and the fence wire then stretched and secured to the fence post, while the wire stretcher is still engaged with 15 the post, thus, preventing the accidental slipping of the wire and retaining the same in a taut condition during the securing operation.

The invention also embraces novel wire 20 gripping means, whereby, any possibility of slippage will be overcome and the wire effectively stretched.

Among other aims and objects of the invention may be recited, the provision of a 25 wire stretcher of the character mentioned with a view to compactness, and in which the number of parts are few, the construction simple, and the cost of production small.

30 All of the foregoing together with additional advantageous details and arrangements of parts of the preferred embodiment of my invention will be clear from the specific description hereinafter contained when 35 read in connection with the accompanying drawings forming a part thereof, wherein said embodiment of the invention is illustrated for the purpose of facilitating a full understanding of the present improvements.

40 In the drawings:

Figure 1 is a top plan of the improved wire stretcher as applied to a fence post and wire, and

Fig. 2 is a side elevation of the supporting frame, the frame being shown in engagement with a portion of a fence post.

Referring now more specifically to the drawings, and in connection with which like reference numerals will indicate the same 50 parts in the several views, the construction embodies a substantially L-shaped supporting frame, indicated in its entirety, by the numeral 1, the frame comprising a post engaging portion 2 and a supporting portion 55 3 which is secured to the former by means of rivets 4 or the like. Angular metal pieces

5 are secured to the outer extremity of the portion 2, as at 6 and afford engaging feet therefor, thus, enabling the construction to be readily engaged with a fence post. To 60 secure the frame 1 upon a fence post, which I have indicated by way of illustration, by the reference character 7, a chain or other flexible element 8 having hooks upon the free ends thereof is passed about the post 7 65 and then engaged, by means of the hooks, with an eyelet 9 arranged upon the base portion of one of the engaging feet 5 as shown in Fig. 2. By this arrangement, it is evident that the frame 1 will be securely 70 maintained in position at all times and that relative movement of the same will be prevented. A plurality of pulleys 10 are girdled within brackets 11 arranged upon 75 either end of the supporting portion 3 of the frame and are adapted to receive thereabout, the wire stretching cable, which will be presently described.

With a view toward providing means 80 whereby the fence wire 12 may be pulled or stretched, there is provided a pulling cable 13, the forward end of which has connected thereto a wire engaging arm 14 which is provided with a clamping cam 15, whereby the fence wire 12 may be engaged therebetween and securely held. The remaining portion of the cable is extended to a point 85 in proximity to the supporting portion 3 of the frame 1, whereat, it is passed about the outermost pulley 10 and is then carried 90 diagonally forward about a floating double sheave pulley 16, which is held in its forward position by means of a cam clamping element, similar to the clamp 15, which is engaged with the remaining portion of the 95 fence wire 12. The cable 13 however being arranged about one sheave of the pulley 16 is passed rearwardly about the remaining pulley 10 and then rearranged about the second or remaining sheave wheel of the 100 pulley 16 and extended for a distance therebeyond, whereby it may be readily engaged by the user of the device for pulling or stretching a wire.

The operation of the construction may be 105 reviewed as follows:

The feet 5 of the frame 1 are engaged with the fence post 7 to which the wire when stretched is to be secured. The clamping elements 15 and 17 are now engaged 110 with the fence wire 12 and a pull imparted about the remaining end of the pulling

cable 13, which action will of course, cause the stretching or drawing of the fence wire 12. When the desired tension has been attained, that portion of the fence wire adjacent the post may be secured thereto by staples or other suitable fastening means and the construction then readily removed for a subsequent operation. By providing a plurality of clamping elements with which 10 to engage the fence wire 12, it is evident that slippage of the wire will be practically eliminated and that the fence wire will be held taut during the securing operation.

As many changes could be made in the 15 above construction and many apparently widely different embodiments of this invention could be made without departing from the scope thereof, it is intended that all matter contained in the above description 20 or shown in the accompanying drawings shall be interpreted as illustrative and not in a limiting sense. It is also to be understood that the language used in the following claims is intended to cover all of the 25 generic and specific features of the invention herein described and all statements of the scope of the invention, which as a matter of language, might be said to fall therebetween.

30 I claim:

1. A wire stretcher, including a frame engageable with a fence post, means for securing the frame to the fence post, a plurality of pulleys arranged upon said frame, 35 a floating pulley, a wire stretching cable arranged about said frame pulleys and said floating pulley, a wire engaging member connected to one end of the wire stretching cable, and a second wire engaging member connected to said floating pulley, where-

by, when the remaining end of the cable is pulled, the fence wire will be stretched.

2. A wire stretcher, including a substantially L-shaped frame engageable with a fence post, a plurality of feet arranged upon one end of the frame to facilitate engagement thereof with the fence post, means for securing the frame to the fence post, a plurality of pulleys arranged upon the frame in spaced apart relation, a floating pulley, 45 a wire stretching cable arranged about the frame pulleys and said floating pulley, a wire engaging member connected to one end of the cable, and a second wire engaging member connected to the floating pulley, 50 whereby, when the cable is pulled the fence wire will be stretched.

3. A wire stretcher including a frame including a post engaging portion, a transverse supporting portion fixedly mounted 60 upon the outer end of said post engaging portion, the ends of said transverse supporting portion projecting beyond the sides of said post engaging portion, pulleys mounted upon the ends of said transverse 65 supporting portion, a double floating pulley, a cable having a clamp upon one end and passing around all of said pulleys, a clamp connected to said floating pulley, the projecting ends of said transverse supporting portion allowing the free movement of 70 said cable without interference from said frame.

In testimony whereof I affix my signature in presence of two witnesses.

JOHN RIEKENS.
